(57) **CLAIM**

The ornamental design for a wheeled stand, as shown and described.

DESCRIPTION

FIG. 1 is a top front perspective view of a wheeled stand showing my new design.

FIG. 2 is a bottom rear perspective view thereof.

FIG. 3 is a front elevation view thereof.

FIG. 4 is a left side elevation view thereof.

FIG. 5 is a right side elevation view thereof.

FIG. 6 is a rear elevation view thereof.

FIG. 7 is a top plan view thereof; and,

FIG. 8 is a bottom plan view thereof.

The broken lines represent portions of the wheeled stand that form no part of the claim.

1 Claim, 6 Drawing Sheets

FIG. 1

FIG. 2

FIG. 3

FIG. 4

FIG. 5

FIG. 6

FIG. 7

FIG. 8
